SUCTION CLEANING APPARATUS

Jack Pickford, Springfield, Mass., assignor to
Westinghouse Electric Corporation, East Pittsburgh, Pa., a corporation of Pennsylvania

Application April 17, 1944, Serial No. 531,314

4 Claims. (CL. 15—14)

1

My invention relates to a suction cleaner which is adapted for use as an ordinary, handle-propelled cleaner in which dirt laden air is drawn through a nozzle moved over the surface to be cleaned, and which may be converted to tank type cleaner in which dirt laden air drawn through an attachment hose applied to the cleaner and in which filtered air may be blown through said hose.

One object of my invention is to provide an improved cleaner of the type set forth.

A further object is to produce an improved converting mechanism for a cleaner of the type set forth.

A still further object of my invention is to produce an improved construction which includes means for locking the attachment hose to the cleaner, and means for insuring the return of the converting mechanism to the position it occupies when the cleaner is used for ordinary floor-nozzle cleaning, before the attachment hose can be disconnected from the cleaner.

These and other objects are effected by my invention as will be apparent from the following description and claims taken in connection with the accompanying drawing, forming a part of this application, in which:

Fig. 1 is a view, partly in section and partly in elevation, of a suction cleaner embodying my invention;

Fig. 2 is an enlarged fragmentary view, in side elevation, of certain details of construction;

Fig. 3 is a view similar to Fig. 2, showing other details of construction;

Fig. 4 is a section on line IV—IV of Fig. 3;

Fig. 5 is a view similar to Fig. 1, showing the suction cleaner converted from floor-nozzle cleaning to attachment suction cleaning;

Fig. 6 is a fragmentary view, partly in section and partly in elevation, showing a modified form of construction with the cleaner adjusted for attachment blowing;

Fig. 7 is a view similar to Fig. 6, showing the cleaner adjusted for attachment suction cleaning; and

Fig. 8 is a section on line VIII—VIII of Fig. 6.

Referring to Fig. 1 of the drawings, my invention is shown applied to a suction cleaner 10 supported on wheels 12 and adapted to be moved over a surface to be cleaned by a suitable pivoted handle (not shown). The cleaner 10 is provided with a floor nozzle 14 in which may be mounted a rotary agitator 16. The cleaner is also provided with a dust bag compartment 18, in which is positioned a dust bag 20, and a fan

2

compartment 22 in which is positioned a fan 24 driven by an electric motor (not shown). The nozzle 14 communicates with the dust bag 20 through a passage 28 and a port 30, and the inlet 25 of the fan 24 communicates with the dust bag compartment 18 through a suitable passage (not shown). The fan compartment 22 is provided with an exhaust outlet 32 formed in a wall 34 of the compartment 22. The outlet 32 communicates with the atmosphere through an opening 36 formed in the cleaner casing.

When used for ordinary floor cleaning, the fan 24 draws air through the nozzle 14, passage 28, port 30, and into dust bag 20 which filters the air. The filtered air is drawn into the inlet of the fan and is discharged into the compartment 22, as shown by the arrows in Fig. 1. With the parts set as shown in Fig. 1, the air is exhausted into the atmosphere through openings 32 and 36. The rotary agitator 16 is driven by the motor actuating the fan 24 by any suitable well-known means (not shown).

In order to be able to convert the cleaner from an ordinary, handle-propelled cleaner to a tank type cleaner, in which dirt laden air may be drawn, or filtered air may be blown through an attachment hose, the cleaner is provided with a passage 38 extending rearwardly from the passage 28 and disposed beneath the fan compartment 22. The passage 38 is formed of a bottom wall 40 and side walls 42 and 44. A portion of the bottom wall 46 of the fan compartment 22 forms the top wall of the passage 38. A hinged valve 48 is movable selectively to connect the passage 28 or the passage 38 with the port 30 and the dust bag 20. The valve 48 is biased by a spring 50 into the position shown in Fig. 1 in which it closes the passage 38 off from the port 30. The top wall 46 is provided with an opening 52 which leads into the passage 38.

The converting mechanism includes a slide 54 which overlies the passage 38 and which is provided with an opening 56. The opening 56 is adapted, in one position of the slide 54, to register with the opening 52 in the wall 46, to establish communication between the fan compartment 22 and the passage 38. The converting mechanism also includes an arm 58 which is carried by the slide 54 and which is movable in an opening 60 in the top wall 46 of the passage 38. The arm 58 is adapted, in one position of the slide, to actuate the valve 48 into the position shown in Fig. 5 in which the nozzle 14 is shut off from the port 30 and in which communication is established between the port 30 and the passage 38. A portion

64 of the slide 54 at all times closes the opening 60 regardless of the position of the slide. The slide 54 also carries a tab 62 which in one position of the slide closes the exhaust opening 32. An adapter 66 is connected to one end of an attachment hose 68, the other end of which may be provided with any desired dusting or blowing tool.

When it is desired to convert the cleaner to suction cleaning through the attachment hose 68, the free end of the adapter 66 is inserted into the passage 38 and the slide 54 is moved inwardly or to the left, as viewed in Fig. 1. This causes the arm 58 to move the valve 48 from the position shown in Fig. 1 to that shown in Fig. 5 in which the nozzle 14 is shut off from the port 30, and in which the passage 38 communicates with the port 30 and the low pressure side of the fan. Dirt laden air is now drawn through the attachment hose 68 into the dust bag 20 and the filtered air is discharged through the exhaust openings 32 and 36.

When it is desired to convert the cleaner so as to blow filtered air through the attachment hose 68, the slide 54 is moved outwardly, or to the right as viewed in Fig. 1, so as to withdraw the arm 58 from contact with the valve 48 and so as to cause the tab 62 to close the outlet opening 32. The opening 56 in the slide now registers with the opening 52, and the valve 48 is biased to the position shown in Fig. 1. Air is drawn through the nozzle 14 into the dust bag, where it is filtered, and the filtered air is drawn by the fan and discharged into the compartment 22 as above explained. The filtered air discharged by the fan 24 into the compartment 22 is exhausted through openings 56 and 52 into the passage 38 and out through the adapter 66 and hose 68.

In order to lock the adapter 66 in position within the passage as long as the cleaner is used for suction cleaning or through the attachment hose or for blowing air through said hose, the end of the adapter 66 is provided with a side pin 70, and the corresponding side wall 42 of the passage 38 is provided with a slot 72 through which the pin 70 is adapted to pass. Positioned adjacent the inner end of the slot 72 is a latch 74 pivoted at 76 and having a cam portion 80 which is adapted to seat in a recess 82 formed in the slide 54. The latch 74 is also provided with a hooked end portion 84 which overlaps the inner portion of the slot 72. A spring 78 normally biases the latch 74 upwardly. When the slide 54 is in the position shown in Fig. 1, the recess 82 therein registers with the cam portion 80 of the latch 74 so that the spring 78 biases the latch 74 upwardly into a position in which the cam portion 80 seats in the recess 82 and the hooked end portion 84 of the latch 74 clears the upper edge of the slot 72 as viewed in Fig. 3. In this position the pin 70 is not engaged by the end 84 of the latch 74. When the slide 54 is moved inwardly or outwardly from the position shown in Fig. 1, the flat portions of the slide on either side of the recess 82 will ride upon the cam portion 80 of the latch 74 and depress the latter into the position shown in Fig. 3 in which the pin 70 is engaged by the hooked end 84 of the latch 74. The adapter 66 is now locked in position until the slide 54 is again moved to the position in which the recess 82 registers with the cam portion 80. It is thus clear that once the adapter 66 is inserted and the slide 54 is moved to either of its converting positions, the conduit 66 cannot be withdrawn from the passage 38 until the slide 54

is returned to the position in which the cleaner is adjusted for floor cleaning through the nozzle 14.

In order to lock the slide 54 in the floor cleaning position of the cleaner until the adapter 66 shall have been inserted into the passage 38, I provide the opposite side of the adapter 66 with another side pin 86 which is adapted to pass through a slot 88 in the opposite side wall 44 of the passage 38. Adjacent the inner end of the slot 88 I provide another latch 90 which is pivoted at 92 and which is provided with a square edged locking portion 94 adapted to engage a correspondingly shaped recess 96 formed in the slide 54. The latch 90 is also provided with a cam portion 98 which overlaps the inner portion of the slot 88. A spring 100 biases the latch 90 upwardly into a position in which the locking portion 94 engages the recess 96 to prevent movement of the slide 54 until the adapter 66 shall have been inserted into the passage 38. When the adapter 66 is inserted into the passage 38, the pin 86 rides on the cam surface 98 to depress the latch 90 into the position shown in Fig. 2 in which the locking portion 94 is disengaged from the recess 96. The slide 54 may now be moved to either of its other positions which movement, as above stated, depresses the latch 74 to lock the pin 70 and hence the adapter 66 within the passage 38. When the slide 54 is returned to its intermediate position to permit disengagement of the pin 70 from the hooked end 84 of the latch 74, the locking portion 94 of the latch 90 engages the recess 96 in the slide 54 to lock the slide in its intermediate position. The cam surface 98 of the latch 90 is provided with a recess or seat 101 which is adapted to be engaged by the pin 86, to retain the adapter 66 in position pending adjustment of the slide 54 and engagement of the latch 74 with the pin 86.

In Figs. 6 to 8 there is shown a modified form of construction in which the structure and operation of the cleaner proper is the same as that shown in Fig. 1 but in which the means for converting the cleaner is somewhat different. In this construction a pair of slides 110 and 112 are used. The slide 110 is provided with an opening 114 which, in one position of said slide, is adapted to register with the opening 52 in the upper wall 46 of the passage 38. The slide 110 also carries the arm 58 for actuating the valve 48. The slide 112 carries the tab 62 which, in one position of the slide 112, closes the opening 32. The slide 112 is also provided with an opening 118 which, in one position of said slide, is adapted to register with the openings 114 and 52. The end of the slide 112 is provided with an upturned lip 120 which is adapted to be engaged by a similar lip 122 on the end of the slide 110 so that the slide 112 will be moved whenever the slide 110 is moved inwardly, or to the left, as viewed in Fig. 6.

When it is desired to use the cleaner for blowing filtered air through the attachment hose 68, the adapter 66 is inserted into the passage 38 and the slides 110 and 112 are both moved outwardly to the position shown in Fig. 6. In this position the tab 62 closes the outlet 32, the openings 114 and 118 register with the opening 52 and the valve 48 shuts the passage 38 off from the port 30 and the low pressure side of the fan 24. Filtered air discharged by the fan 24 into the compartment 22 is now exhausted through the openings 118, 114, 52, the passage 38, the adapter 66 and out through the hose 68.

When it is desired to use the cleaner for suction cleaning through the attachment hose 68,

the slides 110 and 112 are both moved inwardly to the position shown in Fig. 7. In this position the arm 58 moves the valve 48 into a position in which the nozzle 14 is shut off and the passage 38 is placed in communication with the port 30, the dust bag 20 and the low pressure side of the fan 24. It will be noted that in this position the openings 118 and 114 are out of registration with the opening 52 and that the tab 62 does not obstruct the outlet 32. Air is now drawn by the fan 24 through the hose 68 and adapter 66, into the dust bag 20, and the filtered air is exhausted through the open outlets 32 and 38.

When this form of construction is to be used for floor nozzle cleaning, the slide 112 is moved inwardly to take the opening 118 out of registration with the openings 52 and 114 and to move the tab 62 away from the outlet 32. The slide 110 is moved outwardly so as to move the arm 58 away from the valve 48 which is now returned to the position shown in Fig. 6, by the spring 50. The fan 24 now draws air through the nozzle 14, the passage 28, the port 30 and the dust bag 20, and the filtered air is exhausted through the outlets 32 and 38 in the same manner as that described in connection with Fig. 1.

In order to guard against unintended movement of the parts, I provide a plunger 124 which is biased downwardly by a spring 126, and I provide the slide 110 with a cam member 127 including two recesses 128 and 130. The lower end of the plunger 124, which may be rounded as at 132 is adapted to engage one of the recesses 128 or 130 to hold the slide 110 in the position to which it is adjusted. The slide 112 is provided with an opening 136 so that it may be moved independently of the movement of the slide 110 and without affecting the cam member 127. The force of the spring 126 is not sufficient to lock the parts in position but is sufficient to prevent accidental or unintended movement thereof. The end of the adapter 66 may be detachably secured in position within the passage 38 in any desired manner, such as a bayonet coupling, a latch or the like. Since this connection may be conventional it is not shown.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. A suction cleaner comprising a casing, a suction-creating device therein, said casing having a suction nozzle and a discharge outlet, a wall structure defining a passage adjacent a wall of said casing, valve means movable into a plurality of positions for selectively connecting said passage or said nozzle to the low-pressure side of said suction-creating device, valve means movable into a plurality of positions for selectively connecting said passage or said outlet to the high-pressure side of said suction-creating device, valve-actuating means movable into a plurality of positions for selectively actuating either of said valve means into one or the other of its respective positions, an adapter connectible to said passage, a latch carried by the cleaner and normally locking said valve-actuating means against movement, means operable in response to connection of said adapter to said passage to disengage said latch from said valve-actuating means, a second

latch carried by the cleaner, latch-engaging means carried by said adapter, and means operable upon movement of said valve-actuating means to actuate said second latch into engagement with said latch-engaging means to lock said adapter to said passage.

2. A suction cleaner comprising a casing, a suction-creating device therein, said casing having a suction nozzle and a discharge outlet, a wall structure defining a passage adjacent a wall of said casing, valve means for selectively connecting said passage or said nozzle to the low-pressure side of said suction-creating device, valve means movable into a plurality of positions for selectively actuating either of said valve means into one or the other of its positions, an adapter connectible to said passage, a latch carried by the cleaner, a spring normally urging said latch into a position locking said valve-actuating means against movement, a pin carried by and operable upon connection of said adapter to said passage to disengage said latch from said valve-actuating means, a second latch carried by the cleaner, latch-engaging means carried by said adapter, a spring normally urging said second latch out of engagement with said latch-engaging means, and means operable upon movement of said valve-actuating means to actuate said second latch into engagement with said latch-engaging means to lock the adapter to said passage.

3. A suction cleaner comprising a casing, a suction-creating device therein, said casing having a suction nozzle and a discharge outlet, a wall structure defining a passage adjacent a wall of said casing, valve means movable into a plurality of positions for selectively connecting said passage or said nozzle to the low-pressure side of said suction-creating device, valve means movable into a plurality of positions for selectively connecting said passage or said outlet to the high-pressure side of said suction-creating device, valve-actuating means movable into a plurality of positions for selectively actuating either of said valve means into one or the other of their respective positions, an adapter insertable into said passage, a latch carried by a wall of said passage and normally locking said valve-actuating means against movement, and means operable in response to insertion of said adapter into said passage to disengage said latch from said valve actuating means.

4. A suction cleaner comprising a casing, a suction-creating device therein, said casing having a suction nozzle and an attachment suction inlet, valve means movable into a plurality of positions for selectively connecting said nozzle or said inlet to the low-pressure side of said suction-creating device, valve-actuating means movable into a plurality of positions for selectively actuating said valve means into one or the other of said positions, an adapter connectible to said inlet, a latch carried by the casing and normally locking said valve-actuating means in the position to connect said nozzle to the low-pressure side when said adapter is not connected to said inlet, means operable in response to connection of said adapter to said inlet to actuate said latch to release said valve-actuating means, said valve-actuating means being then movable into either of said positions, a second latch carried by the cleaner, latch-engaging means carried by said adapter,

and means operable in response to movement of said valve-actuating means to the position to connect said inlet to the low-pressure side to actuate said second latch into engagement with said latch-engaging means to lock said adapter to said inlet and operable in response to movement of said valve-actuating means to the position to connect said nozzle to the low-pressure side to actuate said second latch out of engagement with said latch-engaging means to release said adapter 10 from said inlet.
